MULTI-PRODUCT DISPENSER FOR TOILETRIES

Melvin Rudin, Mountain View, Calif., assignor to Dynatek, Santa Clara, Calif., a partnership

Filed June 7, 1965, Ser. No. 85,602

Term of patent 7 years

(Cl. D52—2)

FIG. 1. is a front and top isometric view of a multi-product dispenser for toiletries, showing my new design; and

FIG. 2 is a rear and bottom isometric view of the opposite side thereof;

FIG. 3 is a fragmentary perspective view of the dispenser looking upwardly below the overhanging member projecting from the front panel thereof.

I claim:

The ornamental design for a multi-product dispenser for toiletries, substantially as shown.
